UNITED STATES PATENT OFFICE.

ABRAHAM TCHERNIACK, OF NEW YORK, N. Y.

LOOM FOR WEAVING.

No. 12,493.

Specification of Reissued Letters Patent.

Reissued June 5, 1906.

Original No. 807,791, dated December 19, 1905. Application for reissue filed March 7, 1906. Serial No. 304,798.

To all whom it may concern:

Be it known that I, ABRAHAM TCHERNIACK, a subject of the Czar of Russia, residing formerly at The Imperial Technical High School, Moscow, Russia, and at present in the city of New York, N. Y., have invented new and useful Improvements in Looms for Weaving, of which the following is a specification.

10 The improvements which form the subject of this invention relate to the construction of looms for weaving.

The objects of my said invention are (a) to enable two or more pieces of cloth of the same or different widths and texture to be woven simultaneously in one loom, (b) to permit the weft to be introduced into the cloth being woven positively without the shock and noise caused by the use of the fly-20 shuttle, as ordinarily employed, and (c) to economize power and also space by occupying less room relatively to the work produced than looms as ordinarily employed.

In the accompanying drawings, Figure 1 is 25 a side elevation of a circular multifabric loom of this invention. Fig. 2 is a plan view of the frame and beams. Fig. 3 is a section on line A A, Fig. 1, with portions omitted for clearness. Fig. 3^a is a detail of the rack and 30 gear of Fig. 3. Fig. 4 is a side elevation of a portion of the loom, showing driving-shaft and weft-beating mechanism. Fig. 4^a is a side elevation at right angles to Fig. 4 of a detail of the main driving-shaft. Fig. 4^b is a 35 face view of the cam v. Figs. 5 and 5^a are detail plan views of the weft-beating mechanism. Fig. 6 is a sectional plan on line B B, Fig. 1. Fig. 7 is an elevation of a detail of the reciprocating mechanism for the shuttle-carrier. Fig. 8 is a detail of the holder 40 for the shuttle in side elevation. Fig. 9 is an end view, and Fig. 10 is a plan view of Fig. 8.

In the views the same letters refer to like parts.

45 According to my invention I construct a loom which may be arranged either as shown in the drawings, so as to be equal in the means of production to four ordinary looms of the same or different widths, or said loom 50 may be arranged so as to be equal in the means of production to a lesser or a larger number of said ordinary looms by decreasing or increasing the number of beams a b c d, (shown in Fig. 2,) and the complete sectional 55 portion, (shown in Fig. 1,) which, in combination with the beam a, forms an independ-

ent loom. The description of this portion will apply to other sectional portions that are respectively in combination with the beams b, c, and d. The warp-threads e are 60 arranged vertically and are drawn from the beam a over the rounded edge of the bar f. A shuttle-carrier, consisting of a central boss g, Fig. 6, and rings, as g' g² g³, separated from each other by distance-pieces g⁴, secured to 65 said boss by arms, as g⁵, is fitted loosely on a vertical shaft j, placed centrally in the loom. The space in a circular direction between the aforesaid distance-pieces is equal to twice 70 the width of the cloth to be woven plus the length of the shuttle-box and weft-fork with the necessary space for clearance. The shuttle-boxes are formed of plates, as k' and k², which are fixed alternately to the center and outer rings g² and g' and to the center 75 and inner rings g² and g³ in such a manner that the center of the space between the inner edges of said plates is the same as the center of the space between the two rings to which they are fixed, as shown in Fig. 6.

80 The inner ends of the aforesaid plates are curved inward toward each other, forming boat-shaped recesses, in which correspondingly-shaped shuttles l are placed. Said shuttles have a tongue therein on which to 85 place the cop in the ordinary manner. Between the inner surface of the shuttle-box and the outer surface of the shuttle therein is a free space or opening for the passage of the warp-threads, between which the shuttle is 90 caused to traverse for the purpose of introducing the weft. On the opening of a shed in the warp-threads which pass through the space between the rings of the shuttle-carrier opposite their corresponding shuttle-boxes 95 and by revolving said shuttle-carrier with the shuttle-boxes affixed thereto (the number of which corresponds with the number of pieces to be woven simultaneously) the shuttles are passed through the sheds, the warp-threads 100 passing between the inner surfaces of the shuttle-boxes and the outer surfaces of the shuttle, the weft being by these means threaded in. In order to cause the shuttle-carrier to have a reversible semirotary movement, I fit on the shaft n⁵ of the loom either a crank or a disk n, as shown in Figs. 4, 6, and 7, which by means of a connecting-rod n' communicates motion radially to a lever n², pivoted to the frame at n³, Fig. 6. Said lever is either cranked or formed with a slot, as n⁴, so as to pass beyond the central pillar or 105 110

shaft j . The inner end n^4 of the lever n^2 carries a bowl n^5 , which slides in a slot p^2 in the free end of a lever p' , formed on or attached to the boss g on the vertical shaft j .

- 5 The motion of the healds q and q' , which are placed horizontally, is effected by means of a series of racks r , the number of which corresponds to the number of shuttles employed. Said racks gear into a pinion or pinions r' , revolving loosely on either the boss g of the shuttle-carrier or on the shaft j , as shown in Fig. 3, and by means of the link s , the bell-crank lever s' , and a cam s^2 a partially-revolving motion is periodically communicated to the pinion or pinions r' , causing the racks r to have a reciprocating motion, thereby moving the healds which are attached to the racks and forming the necessary shed for the shuttle to pass through.
- 10 15 The eyes of the healds are arranged concentrically with the shuttle-carrier. The slay consists of a disk t , having arms t^x radiating therefrom, to which the reeds u are attached, Figs. 5 and 5^a, each reed forming the segment of a circle. The number of reeds corresponds to the number of shuttles and of pieces of cloth to be woven. The slay has a vertical reciprocating motion derived from a cam v on the main shaft m . A lever v' , pivoted to the frame at x , is connected at one end to the cam v and its opposite end to a boss w , sliding on the vertical shaft j . Said boss is connected by hinged levers w^x , Fig. 4, to the arms t^x , thereby effecting the beating up by raising the reeds u each time the shuttle has passed the shed. I may add springs v^2 v^3 on the shaft j above and below the boss w to take up the inertia of the lever v' in its up-and-down motion and to ease the movements of the boss w . The taking-up motion consists of a suitable train of wheels worked by a pawl and acting on a surface roller, as in an ordinary plain loom.
- 20 25 30 35 40 45 50 55 60 65

In operation motion is imparted to the shaft m , which carries the cam v , so shaped as to actuate the lever v' twice at each revolution. The shaft m , through bevel-gears, operates shaft n^x , which carries the disk n , operating the connecting-rod n' , slotted lever n^2 , and crank-arm p' , so as to reciprocate the shuttle-carrier once at each revolution of the shaft m . The cam s^2 , Fig. 3, may be connected in any suitable manner with said shaft m . I have not illustrated such means in my drawings, as a manner of so doing will be obvious to one skilled in the art. This cam s^2 , through the link s , gear r' , and racks, may change the shed after each reciprocation in one direction of the shuttle-carrier. As the shuttle-carrier moves contra-clockwise from the position of Fig. 6, each shuttle will be carried at a substantially constant speed (not thrown across, as usual) through the shed previously formed by the frames q q' , which have been previously reciprocated. The

open-mouthed ends of the plates k' k^2 , forming the shuttle-holder, guide the shed-threads into the space between the plates, which threads spring out when they have passed the contracted opening of the holder, and one side of the shed passes to one side of the shuttle, while the other side of the shed passes to the other side of the shuttle. The boat-shaped shuttle makes this passage simple, and the shuttle is practically floated upon the warps of the shed while it passes therethrough. Its shape prevents its vertical displacement from becoming so great as to cause it to leave its holder and prevents it from moving out of place horizontally to the trackway. When each shuttle has passed through the shed in which it is to operate, the slays are moved upon their hinged inner ends, as illustrated in dotted lines in Fig. 4, to beat up the weft-thread just inserted by the shuttles, and the frames for the healds are also reciprocated to produce a different arrangement of warp-threads. These two functions should of course be performed before the return of the shuttle and shuttle-carrier in their clockwise direction of motion, which return may now take place and the operation just described be repeated.

I claim as my invention—

1. A loom for weaving having means for forming a number of separate vertical sheds, each on the arc of a circle, and grouped around a common vertical center, and a reciprocating operating mechanism for inserting separate weft-threads in the separate sheds.

2. A loom for weaving, having means for forming a number of separate sheds about a common center, separate shuttle for each shed, and means for reciprocating each shuttle backward and forward through its shed.

3. A loom for weaving, having means for forming a number of separate sheds, each on the arc of a circle, and grouped around a common center, a separate shuttle for each shed, and means for reciprocating each shuttle backward and forward through each shed.

4. A loom for weaving, having means for forming a number of separate sheds each on the arc of a circle and grouped around a common center and a separate shuttle for each shed, and means for carrying each shuttle through its shed at a substantially constant speed and then reversing the direction of its carriages.

5. A loom for weaving a number of fabrics, comprising a circular shuttle-carrier, and means for forming sheds perpendicular thereto, shuttles resting on said carrier, and means for passing said shuttles through the sheds by the movement of the carrier without displacing the shuttles horizontally upon the carrier.

6. A loom having means for carrying vertical warps, and provided with a shuttle-box

- formed of two parts, between which the vertical warp-threads pass, means to form a shed, a shuttle held against horizontal motion upon said shuttle-box, and means to operate said box, whereby, upon such operation, the shuttle will be carried through the shed, one side of which will pass between one side of the shuttle and one part of the box, while the other side of the shed will pass between the other side of the shuttle and the other part of the box.
7. A loom having a shuttle-carrier composed of a number of circular rings, means thereon for holding a shuttle against horizontal motion in the carrier, means for producing a shed passing between two of such rings, a shaft and arms therefrom carrying said rings and means for operating said rings to move them through the shed.
- 15 8. A loom, having a shuttle-carrier, composed of a number of circular rings, means for holding a shuttle against horizontal motion in the carrier, means for producing a shed between two of such rings, a shaft and arms therefrom carrying said rings and means for reciprocating said carrier through the shed.
- 25 9. A loom having means for carrying vertical warps and shed-forming means therefor, a shuttle, and a shuttle-box, the latter being composed of two parts and being so formed as to prevent horizontal displacement of the shuttle and having its ends adapted to permit the shuttle and box to be traversed with the warps of the shed between the inner surfaces of the shuttle-box and the outer surfaces of the shuttle.
- 35 10. A loom for weaving, having means for carrying vertical warps and shed-forming
- means therefor, and a shuttle-box in two parts forming a contracted opening at each end of the box and a shuttle held by gravity therein, the box and shuttle being adapted to be traversed with the warps of the shed between the inner surfaces of the shuttle-box and the outer surfaces of the shuttle.
11. In combination with the shed-forming mechanism of a loom with vertical warps, a shuttle-box composed of plates with a free passage between them, each plate having enlarged ends and a boat-shaped shuttle running in the mid-portion of the shuttle-box.
- 15 12. A loom, having a plurality of separate sheds, and a slay for each shed, said slays being hinged to a common center at one end and operating-arms adapted to move them on their hinges to beat up the weft-threads.
- 25 13. A loom for weaving a number of pieces of fabric at once, comprising a common central axis, a shuttle-carrier composed of a number of rings and means to reciprocate said shuttle-carrier on said common axis, gravity-held shuttles carried by said shuttle-carrier, means to prevent their horizontal motion on said shuttle-carrier, frames carrying the healds arranged about said common center and means for operating them to form the shed, and slays for beating up the weft, likewise arranged about said common center and hinged thereto on their inner ends, and means for moving said slays on their hinged ends.
- In witness whereof I have signed my name to this specification in the presence of two subscribing witnesses.
